(57) **ABSTRACT**

A speaker module and a headset (100) are provided. The speaker module is used for the headset (100). The headset (100) includes a housing (1). The speaker module includes a first speaker unit (4a) and a second speaker unit (4b). An outer surface of a first diaphragm assembly (4a21) of the first speaker unit (4a) faces a first side, the second speaker unit (4b) is located on one side of a circumferential direction of the first speaker unit (4a), the second speaker unit (4b) emits sound toward the first side, and sound emission frequency of the second speaker unit (4b) is greater than sound emission frequency of the first speaker unit (4a).

SPEAKER MODULE AND HEADSET

CROSS-REFERENCE TO RELATED
APPLICATIONS

This application is a national stage of International Application No. PCT/CN2022/114786 filed on Aug. 25, 2022, which claims priority to Chinese Patent Application No. 202111109352.7 filed on Sep. 22, 2021. The disclosures of both of the aforementioned application are hereby incorporated by reference in their entirieties.

TECHNICAL FIELD

This application relates to the field of electronic product technologies, and in particular, to a speaker module and a headset.

BACKGROUND

In a use process of an electronic product, to enable a user to listen, without disturbing others, to sound information provided by the electronic product, a headset has become an essential accessory of the electronic product.

In a related technology, a structural layout of an internal speaker of the headset is improper, resulting in a poor sound output effect of the headset, and therefore needs to be further improved.

SUMMARY

Embodiments of this application provide a speaker module and a headset, to achieve a relatively good sound output effect.

To achieve the foregoing objective, the following technical solutions are used in the embodiments of this application:

According to a first aspect, some embodiments of this application provide a speaker module, used for a headset. The headset includes a housing. The speaker module includes a first speaker unit and a second speaker unit. The first speaker unit includes a first diaphragm assembly, an outer surface of the first diaphragm assembly faces a first side, the second speaker unit is located on one side of a circumferential direction of the first speaker unit, the second speaker unit emits sound toward the first side, and sound emission frequency of the second speaker unit is greater than sound emission frequency of the first speaker unit.

According to the headset in this embodiment of this application, the first speaker unit and the second speaker unit are disposed, and the sound emission frequency of the second speaker unit is greater than the sound emission frequency of the second speaker unit. This helps the headset have relatively good sound expressiveness in ranges of different frequencies by using a sound emission frequency difference between the first speaker unit and the second speaker unit, thereby improving a sound output effect of the speaker module. Furthermore, the second speaker unit is located on one side of the circumferential direction of the first speaker unit. In addition, a sound emission direction of the first speaker unit is the same as a sound emission direction of the second speaker unit. This can prevent the second speaker unit from blocking sound output of the first speaker unit, and can also prevent sound output vibration of the first speaker unit from interfering with the second speaker unit, thereby helping improve an overall sound output effect of the headset. In addition, this can also help

2

improve comfort of a user in wearing the headset, and reduce a volume of the headset.

According to some optional embodiments of this application, an outer circumferential surface of the first speaker unit includes a first contour surface and a second contour surface, and the first contour surface and the second contour surface are arranged and connected along the circumferential direction of the first speaker unit. An inner circumferential surface of the housing includes a first inner circumferential surface region and a second inner circumferential surface region, and the first inner circumferential surface region and the second inner circumferential surface region are arranged and connected along a circumferential direction of the housing. The first contour surface is opposite to and spaced apart from the first inner circumferential surface region, the second contour surface is adapted to the second inner circumferential surface region, and the second speaker unit is located between the first contour surface and the first inner circumferential surface region. In this disposition, on one hand, the first contour surface is spaced apart from the first inner circumferential surface region, so that the second speaker unit can be avoided by using the first contour surface, to provide avoidance space for disposition of the second speaker unit, thereby facilitating disposition of the second speaker unit. On the other hand, the second contour surface is adapted to the second inner circumferential surface region, so that the second contour surface fits with the second inner circumferential surface region, to help set an overall volume of the first speaker unit to be larger on the basis that the first speaker unit provides the second speaker unit with the avoidance space, thereby ensuring an effective vibration area of the diaphragm assembly in the first speaker unit, and improving a sound output effect of the first speaker unit.

According to some optional embodiments of this application, the second inner circumferential surface region is a curved surface extending along the circumferential direction of the housing, and the second contour surface is a curved surface extending along the circumferential direction of the housing. This disposition helps increase a volume of accommodation space in the housing while ensuring that an overall shape of the housing is adapted to an ear of a human body, so that more functional devices are integrated into the headset.

According to some optional embodiments of this application, both the second inner circumferential surface region and the second contour surface are arc-shaped surfaces that extend along the circumferential direction of the housing and that are arched away from the first contour surface. This disposition helps increase a volume of accommodation space in the housing while ensuring that an overall shape of the housing is adapted to an ear of a human body, so that more functional devices are integrated into the headset.

According to some optional embodiments of this application, the first contour surface is a plane, or the first contour surface is an arc-shaped surface arched toward the first inner circumferential surface region. This helps avoid the second speaker unit.

According to some optional embodiments of this application, the first speaker unit includes a first frame, the first diaphragm assembly is supported on the first frame and disposed based on a same central axis as the first frame, a circumferential wall of the first frame includes a first part and a second part, the first part and the second part are arranged and connected along a circumferential direction of the first frame, a surface that is of the first part and that faces away from the second part is formed as the first contour

surface, and a surface that is of the second part and that faces away from the first part is formed as the second contour surface. Therefore, the circumferential wall of the first frame includes the first part and the second part, the surface that is of the first part and that faces away from the second part is formed as the first contour surface, and the surface that is of the second part and that faces away from the first part is formed as the second contour surface, so that the first frame can be used as a casing of the first speaker unit without disposition of an additional casing. Furthermore, a front cavity and a rear cavity of the first speaker unit may be disposed in the housing of the headset, to help increase a volume of the first speaker unit, thereby increasing an effective vibration area of the first diaphragm assembly, and ensuring a sound output effect of the first speaker unit.

According to some optional embodiments of this application, the first diaphragm assembly has a first folded ring, the first folded ring includes a first segment and a second segment, the first segment and the second segment are arranged and connected in the circumferential direction of the first frame, an extending path of the first segment along the circumferential direction of the first frame is the same as an extending path of the first part along the circumferential direction of the first frame, an extending path of the second segment along the circumferential direction of the first frame is the same as an extending path of the second part along the circumferential direction of the first frame, the first segment is located between the first part and the second segment, and the second segment is located between the first segment and the second part. In this disposition, the first diaphragm assembly can be adapted to a shape of the circumferential wall of the first frame, to help improve connection reliability between the first diaphragm assembly and the first frame, and help set a size of the first diaphragm assembly to be larger, thereby ensuring an effective vibration area of the first diaphragm assembly, and improving a sound output effect of the first speaker unit.

According to some optional embodiments of this application, the first diaphragm assembly is symmetrically disposed. When a first voice coil drives the first diaphragm assembly to vibrate, this helps enable the first diaphragm assembly to receive driving forces of a same magnitude on two sides of a symmetry plane of the first diaphragm assembly, thereby helping prevent a rolling vibration phenomenon from occurring on the first diaphragm assembly in a direction perpendicular to the symmetry plane.

According to some optional embodiments of this application, the first segment is equal to the second segment in width. This helps implement piston-type vibration of the first diaphragm assembly, to avoid, to at least a specific degree, a problem that rolling vibration occurs on the first diaphragm assembly.

According to some optional embodiments of this application, the first diaphragm assembly is an integrally formed member. This disposition helps improve structural strength of the first diaphragm assembly, thereby facilitating processing and manufacturing of the first diaphragm assembly.

According to some optional embodiments of this application, an annular groove recessed in a direction away from the central axis of the first frame is disposed on an inner circumferential surface of the first frame, the annular groove extends along the circumferential direction of the first frame and the annular groove penetrates to an end surface of an open end of the first frame, an outer edge of the first diaphragm assembly is accommodated in the annular groove and fastened to a bottom surface of the annular groove. This helps effectively support the first diaphragm assembly by

using the annular groove. In addition, due to disposition of the annular groove, a volume of space in the first frame can be increased, to help set a size of the first diaphragm assembly to be larger, thereby helping increase an effective vibration area of the first diaphragm assembly, and improve a sound output effect of the speaker.

According to some optional embodiments of this application, the first speaker unit includes the first voice coil, and the first voice coil is connected to an inner surface of the first diaphragm assembly. The first voice coil includes a first voice coil part and a second voice coil part that are arranged and connected in the circumferential direction of the first frame, an extending path of the first voice coil part along the circumferential direction of the first frame is the same as the extending path of the first part along the circumferential direction of the first frame, the first voice coil part is located between the first part and the second voice coil part, an extending path of the second voice coil part along the circumferential direction of the first frame is the same as the extending path of the second part along the circumferential direction of the first frame, and the second voice coil part is located between the second part and the first voice coil part. In this disposition, when the first voice coil pushes the first diaphragm assembly to vibrate, uniformity of a driving force of the first voice coil for the first diaphragm assembly in a circumferential direction can be improved to at least a specific degree, and a problem that polarization or rolling vibration occurs on the first diaphragm assembly because a shape of the first voice coil is not adapted to a shape of the first diaphragm assembly can be avoided to at least a specific degree.

According to some optional embodiments of this application, the first speaker unit includes a first magnetic circuit system, the first magnetic circuit system is fastened to the first frame, and the first magnetic circuit system has an annular magnetic gap. The magnetic gap includes a first gap part and a second gap part, the first gap part and the second gap part are arranged and connected in the circumferential direction of the first frame, the first gap part is adapted to the first voice coil part, and the second gap part is adapted to the second voice coil part. In this disposition, a shape of the entire magnetic gap can be adapted to a shape of the first voice coil, to help ensure cooperation reliability between the first voice coil and the first magnetic circuit system. Therefore, when the first voice coil cooperates with the first magnetic circuit system to drive the first diaphragm assembly to vibrate, uniformity of a driving force for the first diaphragm assembly in the circumferential direction of the first frame is ensured, and a problem that rolling vibration occurs on the first diaphragm assembly is avoided. In addition, the first voice coil is connected to a side that is of the first diaphragm assembly and that faces away from a sound output hole, and an end that is of the first voice coil and that is away from the first diaphragm assembly cooperates with the magnetic gap of the first magnetic circuit system. In this way, compared with a solution in which the first voice coil is connected to a side that is of a first dome and that faces the sound output hole, and the end that is of the first voice coil and that is away from the first diaphragm assembly cooperates with the magnetic gap of the first magnetic circuit system, an outer surface that is of the first diaphragm assembly and that faces the sound output hole is not blocked by the first magnetic circuit system or the first voice coil, to help ensure a sound output area of the first diaphragm assembly, and further improve a sound output effect of the first speaker unit.

According to some optional embodiments of this application, the first magnetic circuit system includes an edge magnetic part and a first central magnetic part. The edge magnetic part is annular, the edge magnetic part includes a first subpart and a second subpart, the first subpart and the second subpart are arranged and connected in the circumferential direction of the first frame, an extending path of the first subpart in the circumferential direction of the first frame is the same as the extending path of the first part in the circumferential direction of the first frame, and an extending path of the second subpart in the circumferential direction of the first frame is the same as the extending path of the second part in the circumferential direction of the first frame. The first central magnetic part is surrounded by the edge magnetic part, the first central magnetic part and the edge magnetic part define the magnetic gap, an outer circumferential surface of the first central magnetic part includes a first surface and a second surface, the first surface and the second surface are arranged and connected in the circumferential direction of the first frame, the first surface is opposite to and spaced apart from the first subpart to define the first gap part, and the second surface is opposite to and spaced apart from the second subpart to define the second gap part.

According to some optional embodiments of this application, both the edge magnetic part and the first central magnetic part may be magnetic bodies. Therefore, magnetic circuit intensity of the first magnetic circuit system can be improved.

According to some optional embodiments of this application, the first magnetic circuit system further includes a second central magnetic part, and the second central magnetic part blocks an end that is of the edge magnetic part and that is away from the first diaphragm assembly, to support the first central magnetic part.

According to some optional embodiments of this application, the second central magnetic part and the edge magnetic part may be an integrally formed member. In this way, connection strength between the second central magnetic part and the edge magnetic part is high, thereby helping reliable support of the second central magnetic part for the first central magnetic part.

According to some optional embodiments of this application, the second central magnetic part may be a magnetic conductive material member. In this way, leakage of a magnetic force line can be restricted by using the second central magnetic part, thereby increasing magnetic induction intensity of the first magnetic circuit system.

According to some optional embodiments of this application, the first magnetic circuit system further includes a magnetic conductive yoke, and the magnetic conductive yoke is disposed on a side that is of the first central magnetic part and that faces the first diaphragm assembly. Therefore, leakage of the magnetic force line is restricted by using the first magnetic circuit system, thereby improving driving strength for the first diaphragm assembly.

According to some optional embodiments of this application, an outer circumferential surface of the magnetic conductive yoke is flush with the outer circumferential surface of the first central magnetic part in an axial direction of the first magnetic circuit system. This helps further improve a restriction effect of the magnetic conductive yoke for the magnetic force line, and increase magnetic induction intensity of the first magnetic circuit system. Furthermore, the magnetic conductive yoke does not affect the magnetic gap, thereby helping improve adaption between the first magnetic circuit system and the first voice coil.

According to some optional embodiments of this application, a width of the first gap part is less than a width of the second gap part. This helps increase a driving force received on a side that is of the first diaphragm assembly and that is close to the first part, thereby improving uniformity of a driving force received by the first diaphragm assembly in the circumferential direction of the first frame, and avoiding a problem that rolling vibration occurs on the first diaphragm assembly.

10 According to some optional embodiments of this application, a surface that is of the second speaker unit and that faces away from the first speaker unit is adapted to the first inner circumferential surface region. This disposition helps make full use of space of the housing to implement compactness of a structure, and facilitates cooperation between the second speaker unit and the first speaker unit to separate the front cavity and the rear cavity of the first speaker unit.

According to some optional embodiments of this application, an outer circumferential contour of the first speaker 20 unit is elliptical, and the second speaker unit is located at one end of a length direction of a short axis of the first speaker unit.

According to some optional embodiments of this application, the first speaker unit is a moving-coil woofer.

25 According to some optional embodiments of this application, the second speaker unit is a moving-iron tweeter or a planar voice coil tweeter.

According to some optional embodiments of this application, the second speaker unit includes a protective casing, 30 a second diaphragm assembly, a spring plate, a transmission rod, a second magnetic circuit system, and a second voice coil. The second diaphragm assembly is disposed in the protective casing. The second diaphragm assembly is parallel to an axial direction of the first speaker unit to divide 35 space in the protective casing into a front cavity and a rear cavity, and a sound output channel connected to the front cavity is formed on a side that is of the protective casing and that is adjacent to the sound output hole. The spring plate, the transmission rod, and the second magnetic circuit system 40 are all disposed in the rear cavity, the second magnetic circuit system is coaxially disposed with the second voice coil, an axial direction of the second magnetic circuit system is the same as the axial direction of the first speaker unit, the second magnetic circuit system cooperates with the second voice coil to drive the spring plate to vibrate, and the transmission rod is connected to the spring plate and the second diaphragm assembly. Therefore, a simple structure and a small volume are achieved.

45 In some optional embodiments of this application, the front cavity and the rear cavity of the second speaker unit are arranged on a radial direction of the first speaker unit, and the front cavity is located on a side that is of the rear cavity and that is away from the first speaker unit. This disposition helps reduce sound output interference between the first speaker unit and the second speaker unit.

50 In some optional embodiments of this application, the spring plate includes a first plate body, a second plate body, and a connection plate body. Both the first plate body and the second plate body are disposed in parallel to the second diaphragm assembly, the second plate body is located on a side that is of the first plate body and that is away from the second diaphragm assembly, a support body beyond an edge of the first plate body is disposed at one end of the second plate body, the connection plate body is connected between 55 an end that is of the second plate body and that is away from the support body and an end that is of the first plate body and that is away from the support body, and the support plate

body is connected to the transmission rod. The second magnetic circuit system includes a magnetic conductive part and two magnetic body parts, the magnetic conductive part is annular, an axial direction of the magnetic conductive part is the same as the axial direction of the first speaker unit, and the first plate body is supported on a surface of a side that is of the magnetic conductive part and that is adjacent to the second diaphragm assembly. The two magnetic body parts are disposed in the magnetic conductive part and are oppositely disposed in a radial direction of the magnetic conductive part, and the second plate body penetrates from one end of the axial direction of the magnetic conductive part to the other end of the axial direction of the magnetic conductive part, so that the support body is located outside the magnetic conductive part, and the second plate body is located between the two magnetic body parts.

According to a second aspect, an embodiment of this application provides a headset. The headset includes a housing and the speaker module in the foregoing embodiment. A sound output hole is formed on the housing, the first speaker unit is disposed in the housing, the outer surface of the first diaphragm assembly faces the sound output hole, the second speaker unit is disposed in the housing, and the second speaker unit emits sound toward the sound output hole.

Because the headset provided in this embodiment of this application includes the speaker module according to any one of the foregoing technical solutions, the headset and the speaker module can resolve a same technical problem and achieve a same technical effect.

DESCRIPTION OF EMBODIMENTS

In embodiments of this application, the terms “first”, “second”, and “third” are used for descriptive purposes only, and cannot be construed as indicating or implying relative importance or implicitly indicating a quantity of indicated technical features. Therefore, a feature defined by “first”, “second”, or “third” may explicitly or implicitly include one or more such features.

In the descriptions of the embodiments of this application, it should be noted that unless otherwise specified and defined explicitly, the terms “install”, “connect”, and “connection” should be understood in a broad sense. For example, “connection” may be a detachable connection or a non-detachable connection; or may be a direct connection or an indirect connection through an intermediate medium. Orientation terms such as “front”, “rear”, “inside”, and “outside” mentioned in the embodiments of this application merely refer to directions in the accompanying drawings. Therefore, the used orientation terms are intended for better and clearer description and understanding of the embodiments of this application, and are not intended for indicating or implying that an indicated apparatus or element needs to have a specific orientation or constructed and operated in a specific orientation, and therefore shall not be construed as limitations on the embodiments of this application. The term “a plurality of” means at least two.

In the embodiments of this application, the term “include”, “comprise”, or any other variant thereof is intended to cover non-exclusive inclusion, so that a process, method, article, or apparatus that includes a series of elements includes not only those elements but also other elements that are not explicitly listed, or includes elements inherent to such a process, method, article, or apparatus. Without further limitation, the element defined by the sentence “including a . . .” does not exclude that other identical elements also exist in the process, method, article, or apparatus including the element. Without further limitation, the element defined by the sentence “including a . . .” does not exclude that other identical elements also exist in the process, method, article, or apparatus including the element.

In the embodiments of this application, the term “and/or” is only used to describe an association relationship between associated objects, and indicates that three relationships may

exist. For example, A and/or B may indicate the following three cases: Only A exists, both A and B exist, and only B exists. In addition, the character “/” in this specification generally indicates an “or” relationship between associated objects.

In the embodiments of this application, the qualifiers, such as “parallel”, “perpendicular”, “same direction”, “coaxial”, “same axis”, and “parallel”, used to describe orientation relationships between various components all indicate approximate orientations for which specific errors are allowed.

This application provides a headset **100**. The headset can be used in cooperation with an electronic product such as a mobile phone, a tablet computer, or a notebook computer, to receive sound information provided by the electronic product and output the sound information to a user. The headset **100** is used in cooperation with the electronic product, so that sound of the electronic product can be prevented from being played through a speaker to disturb others. The headset may be a wireless headset, or may be a wired headset.

Refer to FIG. 1 and FIG. 2. FIG. 1 is a schematic diagram of a structure of the headset **100** according to some embodiments of this application. FIG. 2 is a schematic diagram of an exploded structure of the headset **100** shown in FIG. 1. The headset **100** shown in FIG. 1 and FIG. 2 is described by using a wireless headset as an example. In this embodiment, the headset **100** may include a housing **1**, a main board **2**, a battery **3**, a wireless charging module **5**, a wireless communication module **6**, and a speaker **4**.

It may be understood that FIG. 1, FIG. 2, and the following related accompanying drawings merely show examples of some components included in the headset **100**. Actual shapes, actual sizes, actual positions, and actual structures of these components are not limited by FIG. 1, FIG. 2, and the following accompanying drawings. In addition, when the headset **100** is a wired headset, the wired headset may include no battery, wireless communication module, or wireless charging module.

The housing **1** may be used as a carrier of functional devices of the headset **100**, and configured to protect functional devices located in accommodation space **10** in the housing **1**. In addition, when a user wears the headset **100**, the headset **100** is in contact with an ear of the user through the housing **1**. Therefore, to improve comfort of a user in wearing the headset **100**, a shape of the housing **1** may be adapted to a shape of an ear of a human body.

The housing **1** is directly exposed to an external environment, to be in contact with an ear of a human body of a user. Alternatively, the headset **100** is in contact with another external structure through the housing **1**. This inevitably causes a problem that an outer surface of the housing **1** is scratched, corroded, or the like. To avoid this technical problem, the housing **1** may have specific properties such as abrasion resistance, corrosion resistance, and scratch resistance, or the outer surface of the housing **1** is coated with a layer of a functional material used for abrasion resistance, corrosion resistance, and scratch resistance.

An inner circumferential surface of the housing **1** is a curved surface extending along a circumferential direction of the housing **1**. In some examples, the inner circumferential surface of the housing **1** is an arc-shaped surface extending along the circumferential direction of the housing **1**. For another example, the inner circumferential surface of the housing **1** is an elliptical arc-shaped surface extending along the circumferential direction of the housing **1**. In another example, the inner circumferential surface of the

11

housing 1 may be a combination of an arc-shaped surface and an elliptical arc-shaped surface, provided that it is ensured that the inner circumferential surface of the housing 1 is a curved surface. This disposition helps increase a volume of the accommodation space 10 in the housing 1 while ensuring that an overall shape of the housing 1 is adapted to an ear of a human body, so that more functional devices are integrated into the headset 100.

In some embodiments, the housing 1 may be used as an integral structure, that is, the housing 1 may be an integrally formed member, and the integrally formed housing 1 has higher structural strength.

In some other embodiments, the housing 1 may be formed by assembling a plurality of parts. Still referring to FIG. 1 and FIG. 2, in this embodiment, the housing 1 may include a front housing 11 and a rear housing 12. The front housing 11 faces a human ear when the headset 100 is used, and the rear housing 12 faces away from the human ear when the headset 100 is used. The housing 1 is formed by assembling the front housing 11 and the rear housing 12. This can facilitate separate processing of the front housing 11 and the rear housing 12, to help simplify mold structures of the front housing 11 and the rear housing 12, thereby reducing forming difficulty of the front housing 11 and the rear housing 12, and reducing processing and manufacturing difficulty of the housing 1. Specifically, the front housing 11 may be connected to the rear housing 12 through fastening in a buckling manner, or the front housing 11 may be connected to the rear housing 12 through a screw. Alternatively, in another implementation, the front housing 11 may be connected to the rear housing 12 through fastening by using glue or adhesive tape.

A material of the front housing 11 includes but is not limited to hard plastic, metal, and a combination of plastic and metal. To achieve a lightweight headset 100, hard plastic may be selected as the material of the front housing 11.

Referring to FIG. 2, a first accommodation cavity 101 is formed in the front housing 11, and a side that is of the first accommodation cavity 101 and that is adjacent to the rear housing 12 is open. A sound output hole 110 connected to the first accommodation cavity 101 is formed on the front housing 11, and sound of the headset 100 can be conducted to the outside of the headset 100 through the sound output hole 110.

Specifically, the front housing 11 may include a main body part 111 and an extending part 112. The extending part 112 may be located on one side of the main body part 111 and extend in a direction away from the main body part 111. Referring to FIG. 2, the first accommodation cavity 101 may be formed in the main body part 111, and the sound output hole 110 may be formed in the extending part 112. It may be understood that in some other embodiments, the front housing 11 may not include the extending part 112, and the sound output hole 110 is directly disposed on a wall surface of the main body part 111.

To improve comfort of a user in wearing the headset 100, a contact sleeve 13 may be further disposed on the headset 100, and the contact sleeve 13 may be configured to be in contact with an ear of the user. For example, the contact sleeve 13 may be disposed around an outer circumferential surface of the extending part 112, and a shape of the contact sleeve 13 may be similar to a shape of an ear canal of a human body, to improve adaption in wearing the headset 100. In addition, the contact sleeve 13 may be made of a flexible material such as silicone rubber or rubber, to improve comfort of a user in wearing the headset 100.

12

Referring to FIG. 2, a limiting convex rib 1121 may be formed on the outer circumferential surface of the extending part 112, so that when the contact sleeve 13 is disposed around the outer circumferential surface of the extending part 112, the limiting convex rib 1121 can press against the contact sleeve 13, thereby limiting the contact sleeve 13, and reducing a probability that the contact sleeve 13 naturally falls off from the extending part 112. Certainly, to reduce costs, the headset 100 may alternatively not include the contact sleeve 13.

A material of the rear housing 12 may be the same as the material of the front housing 11. Certainly, the material of the rear housing 12 may alternatively be different from the material of the front housing 11. To achieve a lightweight headset 100, hard plastic may be selected as the material of the rear housing 12.

Still referring to FIG. 2, the rear housing 12 may include a shield body 121 and a rod body 122. The shield body 121 may be connected to the front housing 11, and the rod body 122 may be disposed on a side that is of the shield body 121 and that is away from the front housing 11. A second accommodation cavity 102 may be formed in the shield body 121, and a side that is of the second accommodation cavity 102 and that is adjacent to the front housing 11 is open. In this way, the second accommodation cavity 102 can be connected to the first accommodation cavity 101, and the second accommodation cavity 102 and the first accommodation cavity 101 can jointly form the accommodation space 10 in the housing 1.

The shield body 121 and the rod body 122 may be an integral structure, that is, the shield body 121 and the rod body 122 are an integral structure. This can simplify processing and manufacturing techniques of the rear housing 12, and also improve connection strength between the shield body 121 and the rod body 122. Certainly, this application is not limited thereto. The shield body 121 and the rod body 122 may alternatively be formed through assembling, and the shield body 121 and the rod body 122 are connected through gluing, clamping, screwing, welding, or the like.

The main board 2 may be accommodated in the accommodation space 10. Specifically, the main board 2 may be installed in the second accommodation cavity 102. A manner of installing the main board 2 in the housing 1 includes but is not limited to clamping, screwing, or gluing.

The main board 2 is configured to integrate a control chip and the like. The control chip may be, for example, an application processor (application processor, AP), a double data rate (double data rate, DDR) synchronous dynamic random access memory, or a universal flash storage (universal flash storage, UFS). The main board 2 is electrically connected to functional devices such as the wireless communication module 6, the wireless charging module 5, the battery 3, and the speaker 4, to implement operations such as signal control and data signal processing between different functional devices.

The main board 2 may be a rigid printed circuit board, a flexible printed circuit board, or a rigid-flexible printed circuit board. The main board 2 may be an FR-dielectric plate, a Rogers (Rogers) dielectric plate, an FR- and Rogers mixed dielectric plate, or the like. Here, FR- is a code name of a level of a flame-resistant material, and the Rogers dielectric plate is a high-frequency plate.

The wireless communication module 6 may be integrated to the main board 2. For example, the wireless communication module 6 may be fastened to the main board 2 through welding. Optionally, the wireless communication module 6 may be a Bluetooth module, an infrared module,

or a wife module. The headset **100** may exchange a wireless signal with an electronic product by using the wireless communication module **6**, to receive sound information of the electronic product.

The battery **3** is configured to supply power to functional devices such as the main board **2**, the wireless communication module **6**, and the speaker **4** in the headset **100**. The battery **3** may include but is not limited to a nickel-cadmium battery **3**, a nickel-metal hydride battery **3**, a lithium battery **3**, or other types of batteries. In addition, there may be one or more batteries **3** in this embodiment of this application.

A shape of the battery **3** includes but is not limited to a cuboid, a cylinder, a frustum of a cone, or the like. In some examples, the battery **3** may be located in the second accommodation cavity **102**, and the battery **3** is located on a side that is of the main board **2** and that is close to the first accommodation cavity **101**. In another example, the battery **3** may be located on a side that is of the main board **2** and that faces away from the first accommodation cavity **101**. A manner of installing the battery **3** in the housing **1** includes but is not limited to clamping, screwing, or gluing.

The wireless charging module **5** may wirelessly charge the battery **3** of the headset **100**. The wireless charging module **5** may be integrated to the main board **2**. Specifically, refer to FIG. 3. FIG. 3 is a schematic diagram of charging connection between the headset **100** shown in FIG. 1-FIG. 2 and a wireless charging base **200**. In this embodiment, the wireless charging module **5** includes a power receiving coil **51**, an alternating current-to-direct current conversion component **52**, and a charging control component **53**. The power receiving coil **51**, the alternating current-to-direct current conversion component **52**, and the charging control component **53** are all electrically connected to the main board **2**.

The power receiving coil **51** may receive wireless charging input of the wireless charging base **200** of the headset **100**. Certainly, this application is not limited thereto. The power receiving coil **51** may alternatively receive wireless charging input of another terminal supporting wireless charging. The power receiving coil **51** is a receive (Rx) coil. The alternating current-to-direct current conversion component **52** may be an Rx chip.

The wireless charging base **200** includes a power interface **203**, a charging coil **201**, and a direct current-to-alternating current conversion component **202**. The charging coil **201** may be a transmit (Tx) coil. The direct current-to-alternating current conversion component **202** may be a TX chip.

In this embodiment of this application, the wireless charging base **200** is used as a transmit end of a wireless charging signal, the headset **100** is used as a receive end of the wireless charging signal, and the wireless charging base **200** wirelessly charges the headset **100**. Specifically, the direct current-to-alternating current conversion component **202** of the wireless charging base **200** may receive a direct current signal that is input by the power interface **203**. The direct current-to-alternating current conversion component **202** may convert the direct current signal into an alternating current signal, and then input the alternating current signal to the charging coil **201**. The charging coil **201** may generate an alternating electromagnetic field in response to the alternating current signal.

The power receiving coil **51** of the headset **100** is coupled to the charging coil **201**. The power receiving coil **51** (namely, the Rx coil) induces the alternating electromagnetic field emitted by the charging coil **201** (namely, the Tx coil) to generate an alternating current signal, and inputs the alternating current signal to the alternating current-to-direct

current conversion component **52**. The alternating current-to-direct current conversion component **52** may rectify the alternating current signal into a direct current signal, and input the direct current signal to the charging control component **53**. The charging control component **53** may charge the battery **3** based on the direct current signal.

Certainly, this application is not limited thereto. In some other examples, the headset **100** can also support wired charging. Specifically, a charging interface is disposed on the housing **1**, the charging interface is electrically connected to the main board **2**, and the charging interface may be connected to a wired charger (also referred to as a power adapter) to receive charging input provided by the wired charger for the battery **3**. For example, the charging interface may be a universal serial bus (universal serial bus, USB) interface.

The speaker **4** may be installed in the accommodation space **10**, and the speaker **4** is located on a side that is of the battery **2** and that is close to the sound output hole **110**. Specifically, the speaker **4** may be installed in the first accommodation cavity **101**. An assembling manner between the speaker **4** and the housing **1** includes but is not limited to clamping, threading, gluing, or the like. The speaker **4** is electrically connected to the main board **2** to obtain an audio electrical signal such as music or voice, and the speaker **4** can convert the audio electrical signal into a sound signal, and support audio play.

Refer to FIG. 4. FIG. 4 is a cross-sectional view of a partial structure of the headset **100** shown in FIG. 1-FIG. 2. In this embodiment, the speaker **4** is a core **42**. The core **42** includes a diaphragm assembly **421**, a voice coil **422** connected to the diaphragm assembly **421** through fastening, a magnetic circuit system **423** disposed on one side of the diaphragm assembly **421**, and a frame **424** used to install the diaphragm assembly **421** and the magnetic circuit system **423**.

The speaker **4** is fastened in the housing **1** by using the frame **424**, and an assembling manner between the frame **424** and the housing **1** includes but is not limited to clamping, threading, gluing, or the like. In addition, the speaker **4** may divide the housing **1** into a front cavity **C1** and a rear cavity **C2** by using the diaphragm assembly **421**. The voice coil **422**, the magnetic circuit system **423**, and the frame **424** are located in the rear cavity **C2**. The sound output hole **110** is connected to the front cavity **C1**. The voice coil **422** generates an induced magnetic field after being energized, and is displaced under the action of a magnetic force of the magnetic circuit system **423**, to drive the diaphragm assembly **421** to vibrate, thereby pushing air in the front cavity **C1** to vibrate to form a sound wave. The sound wave is output by the sound output hole **110**.

Certainly, this application is not limited thereto. In some other examples, the speaker **4** may further include a casing. The speaker **4** is fastened in the housing **1** by using the casing. The core **42** may be fastened to an inner wall of the casing by using the frame **424**. The speaker **4** may divide the casing into a front cavity and a rear cavity by using the diaphragm assembly **421**, and the front cavity of the casing is connected to the sound output hole **110**.

In the foregoing embodiment, the speaker **4** used in the headset **100** is a moving-coil woofer, and there is one speaker **4**. This enables the headset **100** to have expressiveness in a low-frequency range, and makes manufacturing costs of the headset **100** low. However, the moving-coil woofer has a large vibration mass and a poor transient feature, and mass distribution, diaphragm compliance, and asymmetric distribution of a BL electromagnetic driving

15

force may cause different degrees of rocking vibration and different frequencies of split vibration. As a result, a high-frequency response causes a serious peak and valley, and expressiveness in a high-frequency range cannot be implemented. Consequently, a property of the headset 100 in playing audio through the speaker is relatively poor, and a sound effect is poor.

To resolve this technical problem, refer to FIG. 5. FIG. 5 is a cross-sectional view of the headset 100 according to some other embodiments of this application. In this embodiment, instead of disposing one speaker in the headset 100, a plurality of different speakers are integrated to the headset 100. Specifically, the headset 100 may include a speaker module, and the speaker module includes a first speaker unit 4a and a second speaker unit 4b.

Both the first speaker unit 4a and the second speaker unit 4b may be disposed in the housing 1, and an outer surface of a diaphragm assembly in the first speaker unit 4a faces the sound output hole 110, so that the first speaker unit 4a can emit sound toward the sound output hole 110. In addition, the second speaker unit 4b also emits sound toward the sound output hole 110. Therefore, a sound emission direction of the first speaker unit 4a is the same as a sound emission direction of the second speaker unit 4b. Furthermore, sound emission frequency of the second speaker unit 4b is greater than sound emission frequency of the first speaker unit 4a. Therefore, the headset 100 includes the first speaker unit 4a and the second speaker unit 4b. This helps the headset 100 have relatively good sound expressiveness in ranges of different frequencies by using a sound emission frequency difference between the first speaker unit 4a and the second speaker unit 4b, thereby improving a sound output effect of the speaker module.

It should be explained that the “outer surface” of the diaphragm assembly in the first speaker unit 4a is a surface that is of the diaphragm assembly in the first speaker unit 4a and that faces away from the inside of the first speaker unit 4a, and a surface that is of the diaphragm assembly and that is opposite to the “outer surface” is an “inner surface”.

Specifically, in this embodiment, the first speaker unit 4a may be used as a woofer, and the first speaker unit 4a may have a same structure as the speaker 4. For example, the first speaker unit 4a may be a moving-coil woofer. The second speaker unit 4b may be a tweeter. For example, the second speaker unit 4b may be a moving-iron tweeter or a planar voice coil tweeter.

In this embodiment of this application, the first speaker unit 4a is used as a woofer, and the second speaker unit 4b is used as a tweeter, so that the headset 100 can have expressiveness in both a low-frequency range and a high-frequency range, thereby improving a sound output effect of the speaker module.

Still referring to FIG. 5, the second speaker unit 4b and the first speaker unit 4a are arranged and spaced apart in a sound output direction of the sound output hole 110. Specifically, the first speaker unit 4a is located in the main body part 111, and the second speaker unit 4b is located in the extending part 112. In this embodiment, to facilitate placement of the second speaker unit 4b, a size of the extending part 112 needs to be designed to be relatively large. However, because the extending part 112 needs to cooperate with a human ear when the headset 100 is worn, an oversized extending part 112 causes a relatively large overall size of the housing 1 of the headset 100, and is also likely to bring uncomfortable wearing experience to a user. In addition, the second speaker unit 4b occupies space of the extending part 112, and consequently sound emission of the first speaker

16

unit 4a is blocked, affecting a sound output effect of the first speaker unit 4a. In addition, because sound transmission is implemented through air vibration, sound output vibration of the first speaker unit 4a inevitably interferes with vibration of a diaphragm assembly in the second speaker unit 4b, affecting sound output of the second speaker unit 4b. As a result, an overall sound output effect of the headset 100 deteriorates.

The problem that the second speaker unit 4b and the first speaker unit 4a are spaced apart in the sound output direction of the sound output hole 110 and consequently a size of the extending part 112 is large can be resolved by disposing, in a magnetic circuit system of the first speaker unit 4a, a groove for accommodating the second speaker unit 4b. However, this disposition manner still cannot resolve the problem that the second speaker unit 4b blocks sound emission of the first speaker unit 4a and sound output vibration of the first speaker unit 4a interferes with vibration of the diaphragm assembly in the second speaker unit 4b. Therefore, to resolve the foregoing technical problem, refer to FIG. 6, FIG. 7, and FIG. 8. FIG. 6 is a schematic diagram of the headset 100 according to still some other embodiments of this application. FIG. 7 is a schematic diagram of a structure of a cross section of the headset 100 shown in FIG. 6. FIG. 8 is a schematic diagram of a structure of a cross section of the headset 100 shown in FIG. 6. In this embodiment, in terms of an arrangement manner, the first speaker unit 4a and the second speaker unit 4b are no longer arranged along the sound output direction of the sound output hole 110. Instead, the first speaker unit 4a and the second speaker unit 4b are arranged side by side, and the second speaker unit 4b is located on one side of a circumferential direction of the first speaker unit 4a.

This can prevent the second speaker unit 4b from blocking sound output of the first speaker unit 4a, and can also prevent sound output vibration of the first speaker unit 4a from interfering with the second speaker unit 4b, thereby helping improve an overall sound output effect of the headset 100. Furthermore, this can also avoid the problem that the first speaker unit 4a is disposed in the main body part 111 and the second speaker unit 4b is disposed in the extending part 112 and consequently a volume of the extending part 112 is large, affecting experience of a user in wearing the headset 100, thereby helping improve comfort of the user in wearing the headset 100, and reducing a volume of the headset 100.

According to the headset 100 in this embodiment of this application, the first speaker unit 4a and the second speaker unit 4b are disposed, and the sound emission frequency of the second speaker unit 4b is greater than the sound emission frequency of the first speaker unit 4a. This helps the headset 100 have relatively good sound expressiveness in ranges of different frequencies by using a sound emission frequency difference between the first speaker unit 4a and the second speaker unit 4b, thereby improving a sound output effect of the speaker 4. Furthermore, the second speaker unit 4b is located on one side of the circumferential direction of the first speaker unit 4a, and both the first speaker unit 4a and the second speaker unit 4b emit sound toward the sound output hole 110. This can prevent the second speaker unit 4b from blocking sound output of the first speaker unit 4a, and can also prevent sound output vibration of the first speaker unit 4a from interfering with the second speaker unit 4b, thereby helping improve an overall sound output effect of the headset 100. Furthermore, this can also improve comfort of the user in wearing the headset 100, and reduce a volume of the headset 100.

Still refer to FIG. 8, and refer to FIG. 9A. FIG. 9A is a schematic diagram of a structure of the first speaker unit 4a in the headset 100 shown in FIG. 6-FIG. 8. In this embodiment, the inner circumferential surface of the housing 1 includes a first inner circumferential surface region 10a and a second inner circumferential surface region 10b, and the first inner circumferential surface region 10a and the second inner circumferential surface region 10b are arranged and connected along the circumferential direction of the housing 1.

Still referring to FIG. 8 and FIG. 9A, an outer circumferential surface of the first speaker unit 4a includes a first contour surface 4aa and a second contour surface 4ab. The first contour surface 4aa and the second contour surface 4ab are arranged and connected in the circumferential direction of the first speaker unit 4a.

The first contour surface 4aa is opposite to and spaced apart from the first inner circumferential surface region 10a, and the second speaker unit 4b is located between the first contour surface 4aa and the first inner circumferential surface region 10a. The second contour surface 4ab is adapted to the second inner circumferential surface region 10b.

In this disposition, on one hand, the first contour surface 4aa is spaced apart from the first inner circumferential surface region 10a, so that the second speaker unit 4b can be avoided by using the first contour surface 4aa, to provide avoidance space for disposition of the second speaker unit 4b, thereby facilitating disposition of the second speaker unit 4b. On the other hand, the second contour surface 4ab is adapted to the second inner circumferential surface region 10b, to help fitting disposition of the second contour surface 4ab and the second inner circumferential surface region 10b, to help set an overall volume of the first speaker unit 4a to be larger on the basis that the first speaker unit 4a provides the second speaker unit 4b with the avoidance space, thereby ensuring an effective vibration area of the diaphragm assembly in the first speaker unit 4a, and improving a sound output effect of the first speaker unit 4a.

It should be noted that the effective vibration area of the diaphragm assembly in this specification is an area of a part that is of the diaphragm assembly and that can push air to move. The effective vibration area of the diaphragm assembly is related to vibration frequency. A smaller effective vibration area of the diaphragm assembly indicates higher vibration frequency. Correspondingly, a larger effective vibration area of the diaphragm assembly indicates lower vibration frequency.

The second inner circumferential surface region 10b is a curved surface extending along the circumferential direction of the housing 1, and the second contour surface 4ab is a curved surface extending along the circumferential direction of the housing 1. Specifically, referring to FIG. 8, the second inner circumferential surface region 10b is an arc-shaped surface that extends along the circumferential direction of the housing 1 and that is arched away from the first inner circumferential surface region 10a, for example, a major-arc-shaped surface, and the second contour surface 4ab is an arc-shaped surface that extends along the circumferential direction of the housing 1 and that is arched away from the first contour surface 4aa, for example, a major-arc-shaped surface. For example, the inner circumferential surface of the housing 1 is a cylindrical surface, and the second contour surface 4ab is an arc-shaped surface extending along the circumferential direction of the housing 1. It may be understood that a shape of the second contour surface 4ab may be

another shape, provided that it is ensured that the second contour surface 4ab is adapted to the inner circumferential surface of the housing 1.

To space the first contour surface 4aa apart from the first inner circumferential surface region 10a, reduce space occupied by the first speaker unit 4a in the housing 1, and ensure that the second speaker unit 4b can be integrated when the first speaker unit 4a is disposed, for example, the first contour surface 4aa is a plane. For another example, the first contour surface 4aa is an arc-shaped surface extending along the circumferential direction of the housing 1, and the first contour surface 4aa is arched toward the first inner circumferential surface region 10b.

It may be understood that an implementation of setting a position of the second speaker unit 4b based on a shape of the outer circumferential surface of the first speaker unit 4a is not limited thereto. In another embodiment, refer to FIG. 9B. FIG. 9B is a schematic diagram of a structure of a cross section of the headset 100 according to some other embodiments of this application. An outer circumferential contour of the first speaker unit 4a may be elliptical, and the second speaker unit 4b may be located at one end of a length direction of a short axis of the elliptical first speaker unit 4a. Specifically, the inner circumferential surface of the housing 1 is a cylindrical surface, the outer circumferential contour of the first speaker unit 4a may be elliptical, and the second speaker unit 4b may be located at one end of the length direction of the short axis of the elliptical first speaker unit 4a.

As described above, to provide avoidance space for disposition of the second speaker unit 4b, a shape of the first speaker unit 4a is improved. To ensure that a sound output effect of the first speaker unit 4a is not affected by a change of the shape of the first speaker unit 4a, structures of components of the first speaker unit 4a are also adaptively adjusted based on the change of the shape of the first speaker unit 4a. In the following description, the structure of the first speaker unit 4a is described in detail by using an example in which the first contour surface 4aa is a plane and the second contour surface 4ab is an arc-shaped surface extending along the circumferential direction of the housing 1. After reading this application, a person skilled in the art may understand that when the outer circumferential surface of the first speaker unit 4a is in another shape (for example, when the outer circumferential contour of the first speaker unit 4a is an ellipse extending along the circumferential direction of the housing 1), an overall structure of the first speaker unit 4a needs to be adaptively adjusted based on a change of the shape of the first speaker unit 4a.

Refer to FIG. 10. FIG. 10 is a schematic diagram of an exploded structure of the first speaker unit 4a shown in FIG. 9A. In this embodiment, the first speaker unit 4a includes a first frame 4a24, a first diaphragm assembly 4a21, a first voice coil 4a22, and a first magnetic circuit system 4a23. The first frame 4a24, the first diaphragm assembly 4a21, the first voice coil 4a22, and the first magnetic circuit system 4a23 are coaxially disposed.

The first diaphragm assembly 4a21 is a main body that pushes air in a front cavity X1 of the first speaker unit 4a to move. When the first speaker unit 4a shown in FIG. 10 is applied to the housing 1 of the headset 100, referring back to FIG. 7, the first speaker unit 4a divides space in the housing 1 into the front cavity X1 and a rear cavity X2 by using the first diaphragm assembly 4a21 and the second speaker unit 4b.

To improve a sealing effect of the rear cavity X2, sealant 7 may be disposed between the second contour surface 4ab

of the first speaker unit **4a** and the second inner circumferential surface region **10b** and between the first contour surface **4aa** of the first speaker unit **4a**, the second speaker unit **4b**, and the first inner circumferential surface region **10a**. The sealant **7** includes but is not limited to one or more of UV glue (also referred to as shadowless glue), polyurethane, silicone rubber, polysulfide rubber, chloroprene rubber, and epoxy resin sealant. A gap between the inner circumferential surface of the housing **1** and each of the first speaker unit **4a** and the second speaker unit **4b** may be sealed by using the sealant, so that the rear cavity **K2** is formed as a closed cavity. This structure is simple and easy to operate, is suitable for sealing gaps of different shapes, and has a wide application range and relatively good flexibility. The sealant **7** further pastes the first speaker unit **4a** and the second speaker unit **4b** to the housing **1**, to improve connection stability between the housing **1** and each of the first speaker unit **4a** and the second speaker unit **4b**.

It may be understood that FIG. 10 and the following related accompanying drawings merely show examples of some components included in the first speaker unit **4a**. Actual sizes, actual positions, and actual structures of these components are not limited by FIG. 10 and the following accompanying drawings.

Specifically, the first frame **4a24** is used as a “support frame” of the first speaker unit **4a** to support the first diaphragm assembly **4a21**, the first voice coil **4a22**, and the first magnetic circuit system **4a23**.

A material of the first frame **4a24** includes but is not limited to metal, plastic, and a combination of metal and plastic. To improve support reliability of the first frame **4a24**, metal may be selected as the material of the first frame **4a24**. For example, the material of the first frame **4a24** is copper, iron, or aluminum.

The first frame **4a24** may be an integrally formed member, that is, the first frame **4a24** is an integral structure. This helps improve connection strength of the first frame **4a24**. Certainly, this application is not limited thereto. The first frame **4a24** may alternatively be formed by assembling different components, and a plurality of different components may be connected through clamping, threading, gluing, welding, or the like.

Still refer to FIG. 10, and refer to FIG. 11. FIG. 11 is a schematic diagram of a structure of the first frame **4a24** shown in FIG. 10. In this embodiment, the first frame **4a24** includes an annular circumferential wall **4a241** and a bottom wall **4a242**. The circumferential wall **4a241** and the housing **1** may be coaxially disposed. An end that is of the circumferential wall **4a241** and that is away from the sound output hole **110** is connected to the bottom wall **4a242**. This can define internal space of the first frame **4a24**, to facilitate installation of the first diaphragm assembly **4a21**, the first voice coil **4a22**, and the first magnetic circuit system **4a23**.

Still referring to FIG. 11, the circumferential wall **4a241** includes a first part **4a2411** and a second part **4a2412**. The first part **4a2411** and the second part **4a2412** are arranged and connected in a circumferential direction of the first frame **4a24**.

The first part **4a2411** is in a shape of a slate, so that a surface that is of the first part **4a2411** and that faces away from the second part **4a2412** is formed as the first contour surface **4aa**. An extending path of the second part **4a2412** along the circumferential direction of the first frame **4a24** is arc-shaped, so that a surface that is of the second part **4a2412** and that faces away from the first part **4a2411** is formed as the second contour surface **4ab**. In this disposition, the first frame **4a24** can be directly used as a casing of

the first speaker unit **4a** without disposition of an additional casing. This can simplify the structure of the first speaker unit **4a**, and reduce costs. In addition, this helps set a size of the first speaker unit **4a** to be larger, thereby increasing an effective vibration area of the first diaphragm assembly **4a21**, and ensuring a sound output effect of the first speaker unit **4a**.

Refer to FIG. 12 and FIG. 13. FIG. 12 is a schematic diagram of another direction of the first speaker unit **4a** shown in FIG. 9A. FIG. 13 is a schematic diagram of a structure of a cross section of the first speaker unit **4a** shown in FIG. 12 along a line C-C. In this embodiment, an outer edge of the first diaphragm assembly **4a21** is connected to an inner circumferential wall of the first frame **4a24**.

Specifically, refer to FIG. 13, and refer to FIG. 14. FIG. 14 is an enlarged view of a circled part D of the first speaker unit **4a** shown in FIG. 13. In this embodiment, an annular groove **4a2413** recessed toward a direction away from a central axis of the first frame **4a24** is disposed on an inner circumferential surface of the first frame **4a24**, the annular groove **4a2413** extends to be annular along the circumferential direction of the first frame **4a24**, the annular groove **4a2413** penetrates to an end surface of an open end of the first frame **4a24**, namely, an end surface of an end facing the sound output hole **110**, and the outer edge of the first diaphragm assembly **4a21** is accommodated in the annular groove **4a2413** and fastened to a bottom surface of the annular groove **4a2413**. The outer edge of the first diaphragm assembly **4a21** is accommodated in the annular groove **4a2413** and fastened to the bottom surface of the annular groove **4a2413**. This helps effectively support the first diaphragm assembly **4a21** by using the annular groove **4a2413**. In addition, due to disposition of the annular groove **4a2413**, a volume of space in the first frame **4a24** can be increased, to help set a size of the first diaphragm assembly **4a21** to be larger, thereby helping increase an effective vibration area of the first diaphragm assembly **4a21**, and improve a sound output effect of the speaker **4**. It may be understood that the annular groove **4a2413** may not be disposed on the first frame **4a24**, and the outer edge of the first diaphragm assembly **4a21** may be directly connected to the inner circumferential wall **4a241** of the first frame **4a24**.

Refer to FIG. 15A. FIG. 15A is a schematic diagram of a structure of the first diaphragm assembly **4a21** shown in FIG. 10. In this embodiment, the first diaphragm assembly **4a21** includes a first connection part **4a211**, a first folded ring **4a212**, and a first dome **4a213**.

An outer circumferential edge of the first folded ring **4a212** is connected to an inner circumferential edge of the first connection part **4a211**, so that a shape of the inner edge of the first connection part **4a211** is adapted to a shape of the outer edge of the first folded ring **4a212**. An outer edge of the first dome **4a213** is connected to an inner edge of the first folded ring **4a212**, so that a shape of the inner edge of the first folded ring **4a212** is adapted to a shape of the outer edge of the first dome **4a213**.

Specifically, referring to FIG. 15A, and referring to FIG. 14, the first connection part **4a211** is in a shape of an annular plate. The first connection part **4a211** is disposed on the bottom surface of the annular groove **4a2413** in a stacked manner, so that the first diaphragm assembly **4a21** is connected to the first frame **4a24** by using the first connection part **4a211**. A connection manner between the first connection part **4a211** and the annular groove **4a2413** includes but is not limited to gluing, clamping, welding, or screwing.

The first connection part **4a211** includes a first connection segment **4a2111** and a second connection segment **4a2112**.

The first connection segment **4a2111** and the second connection segment **4a2112** are arranged and connected in the circumferential direction of the first frame **4a24**.

Specifically, still refer to FIG. 15A, and refer to FIG. 15B. FIG. 15B is a schematic diagram of assembling between the first diaphragm assembly **4a21** and the first frame **4a24** shown in FIG. 10. The first connection segment **4a2111** linearly extends in the circumferential direction of the first frame **4a24**, and the first connection segment **4a2111** is located between the first part **4a2411** and the second connection segment **4a2112**. In this way, an extending path of the first connection segment **4a2111** in the circumferential direction of the first frame **4a24** can be the same as an extending path of the first part **4a2411** in the circumferential direction of the first frame **4a24**, so that the first connection segment **4a2111** is correspondingly adapted to the first part **4a2411**.

The second connection segment **4a2112** extends to be arc-shaped along the circumferential direction of the first frame **4a24**, and the second connection segment **4a2112** is located between the second part **4a2412** and the first connection segment **4a2111**. In this way, an extending path of the second connection segment **4a2112** in the circumferential direction of the first frame **4a24** can be the same as the extending path of the second part **4a2412** in the circumferential direction of the first frame **4a24**, so that the second connection segment **4a2112** is correspondingly adapted to the second part **4a2412**. Specifically, the second connection segment **4a2112** and the second part **4a2412** have a same central axis.

The first folded ring **4a212** includes a first segment **4a2121** and a second segment **4a2122**. The first segment **4a2121** and the second segment **4a2122** are arranged and connected in the circumferential direction of the first frame **4a24**.

The first segment **4a2121** linearly extends in the circumferential direction of the first frame **4a24**, and the first segment **4a2121** is located between the first connection segment **4a2111** and the second segment **4a2122**. In this way, an extending path of the first segment **4a2121** in the circumferential direction of the first frame **4a24** is the same as the extending path of the first part **4a2411** in the circumferential direction of the first frame **4a24**, so that the first segment **4a2121** can correspond to the first part **4a2411**.

The second segment **4a2122** extends to be arc-shaped in the circumferential direction of the first frame **4a24**, and the second segment **4a2122** is located between the second connection segment **4a2112** and the first segment **4a2121**. In this way, an extending path of the second segment **4a2122** along the circumferential direction of the first frame **4a24** is the same as the extending path of the second part **4a2412** along the circumferential direction of the first frame **4a24**, so that the second segment **4a2122** corresponds to the second part **4a2412**. Specifically, the second segment **4a2122** and the second part **4a2412** have a same central axis.

According to the first diaphragm assembly **4a21** in this embodiment of this application, shapes of the first connection part **4a2111**, the first folded ring **4a212**, and the first dome **4a213** of the first diaphragm assembly **4a21** are all adapted to a shape of the circumferential wall **4a241** of the first frame **4a24**, to help improve connection reliability between the first diaphragm assembly **4a21** and the first frame **4a24**, and help set a size of the first diaphragm assembly **4a21** to be larger, thereby ensuring an effective vibration area of the first diaphragm assembly **4a21**, and improving a sound output effect of the first speaker unit **4a**.

It may be understood that the shapes of the first connection part **4a2111**, the first folded ring **4a212**, and the first dome **4a213** are all adapted to the shape of the circumferential wall **4a241** of the first frame **4a24**. In this way, the first diaphragm assembly **4a21** is in a symmetric shape. Refer to FIG. 16. FIG. 16 is a schematic diagram of another direction of the first diaphragm assembly **4a** shown in FIG. 15A. In this example, the first diaphragm assembly **4a21** is symmetrically disposed by using a plane **m1m1** that passes through an axis of the second segment **4a2122** and that is perpendicular to the first segment **4a2121** as a symmetry plane. In this way, when the first voice coil **4a22** drives the first diaphragm assembly **4a21** to vibrate, this helps enable the first diaphragm assembly **4a21** to receive driving forces of a same magnitude on two sides of the symmetry plane, thereby helping prevent a rolling vibration phenomenon from occurring on the first diaphragm assembly **4a21** in a direction perpendicular to the symmetry plane.

The first diaphragm assembly **4a21** is symmetrically disposed in a direction perpendicular to the first segment **4a2121**. However, because a shape and a size of the first segment **4a2121** are different from a shape and a size of the second segment **4a2122**, asymmetric disposition between the first segment **4a2121** and the second segment **4a2122** is caused, that is, the first segment **4a2121** and the second segment **4a2122** cannot be symmetrical with respect to a plane **m2m2** in FIG. 16. The plane **m2m2** is perpendicular to the plane **m1m1** and passes through the axis of the second segment **4a2122**. Therefore, when the first voice coil **4a22** drives the first diaphragm assembly **4a21** to vibrate, there is a large difference in magnitudes of driving forces received by the first diaphragm assembly **4a21** on two sides of the plane **m2m2**. As a result, the first diaphragm assembly **4a21** cannot vibrate in a piston type, and the first diaphragm assembly **4a21** has a risk of rolling vibration in a direction perpendicular to the plane **m2m2**. To reduce a difference between driving forces received by the first diaphragm assembly **4a21**, the first segment **4a2121** is equal to the second segment **4a2122** in width.

In some examples, the first diaphragm assembly **4a21** is an integrally formed member. That is, the first connection part **4a2111**, the first folded ring **4a212**, and the first dome **4a213** are an integral structure. This disposition helps improve structural strength of the first diaphragm assembly **4a21**, thereby facilitating processing and manufacturing of the first diaphragm assembly **4a21**. Certainly, this application is not limited thereto. Alternatively, after the first connection part **4a2111**, the first folded ring **4a212**, and the first dome **4a213** are separately processed, the first connection part **4a2111** and the first folded ring **4a212** may be connected through gluing, and the first folded ring **4a212** and the first dome **4a213** may be connected through gluing.

Based on the foregoing embodiments, refer to FIG. 17A, and refer to FIG. 13 together. FIG. 17A is a schematic diagram of a structure of the first voice coil **4a22** shown in FIG. 10. The first voice coil **4a22** is connected to an inner surface (namely, a surface of a side facing away from the sound output hole **110**) of the first dome **4a213**. A connection manner between the first voice coil **4a22** and the first dome **4a213** includes but is not limited to gluing.

The first voice coil **4a22** includes a first voice coil part **4a221** and a second voice coil part **4a222**, and the first voice coil part **4a221** and the second voice coil part **4a222** are arranged and connected in the circumferential direction of the first frame **4a24**.

Refer to FIG. 17A and FIG. 17B. FIG. 17B is a schematic diagram of cooperation between the first voice coil **4a22**, the

first frame **4a24**, and the first magnetic circuit system **4a23** shown in FIG. 10. The first voice coil part **4a221** is formed in a shape of a slate parallel to the first part **4a2411**, and the first voice coil part **4a221** is located between the first part **4a2411** and the second voice coil part **4a222**. In this way, an extending path of the first voice coil part **4a221** in the circumferential direction of the first frame **4a24** is the same as the extending path of the first part **4a2411** in the circumferential direction of the first frame **4a24**, so that the first voice coil part **4a221** can correspond to the first part **4a2411**.

The second voice coil part **4a222** extends to be arc-shaped in the circumferential direction of the first frame **4a24**. The second voice coil part **4a222** is located between the second part **4a2412** and the first voice coil part **4a221**. In this way, an extending path of the second voice coil part **4a222** along the circumferential direction of the first frame **4a24** is the same as the extending path of the second part **4a2412** along the circumferential direction of the first frame **4a24**, so that the second voice coil part **4a222** can correspond to the second part **4a2412**. Specifically, the second voice coil part **4a222** and the second part **4a2412** have a same central axis.

According to the first voice coil **4a22** in this embodiment of this application, the first voice coil **4a22** includes the first voice coil part **4a221** and the second voice coil part **4a222**, the first voice coil part **4a221** and the second voice coil part **4a222** are arranged and connected in the circumferential direction of the first frame **4a24**, the extending path of the first voice coil part **4a221** in the circumferential direction of the first frame **4a24** is the same as the extending path of the first part **4a2411** in the circumferential direction of the first frame **4a24**, and the extending path of the second voice coil part **4a222** along the circumferential direction of the first frame **4a24** is the same as the extending path of the second part **4a2412** along the circumferential direction of the first frame **4a24**. Therefore, a shape of the first voice coil **4a22** is adapted to shapes of the first diaphragm assembly **4a21** and the first frame **4a23**. This helps implement compactness of the structure of the first speaker unit **4a**. Furthermore, when the first voice coil **4a22** pushes the first diaphragm assembly **4a21** to vibrate, this can improve uniformity of a driving force of the first voice coil **4a22** for the first diaphragm assembly **4a21** in a circumferential direction to at least a specific degree, and can avoid, to at least a specific degree, a problem that polarization or rolling vibration occurs on the first diaphragm assembly **4a21** because a shape of the first voice coil **4a22** is not adapted to a shape of the first diaphragm assembly **4a21**.

Further, to ensure effective vibration at a center of the first dome **4a213** and effective push of the first voice coil **4a22** for the first diaphragm assembly **4a21**, an outer circumferential surface of the first voice coil **4a22** is flush with an outer circumferential surface of the first dome **4a213** along an axial direction of the first voice coil **4a22**.

Based on the foregoing embodiments, refer to FIG. 18, and refer to FIG. 13 together. FIG. 18 is a schematic diagram of a structure of the first magnetic circuit system **4a23** shown in FIG. 10. The first magnetic circuit system **4a23** has an annular magnetic gap **4a23a**, and an end that is of the first voice coil **4a22** and that is away from the first diaphragm assembly **4a21** can extend into the magnetic gap **4a23a**, so that the first magnetic circuit system **4a23** can cooperate with the first voice coil **4a22** to drive the first diaphragm assembly **4a21** to synchronously vibrate.

Furthermore, the first magnetic circuit system **4a23** is fastened to the first frame **4a24**. Specifically, an installation through hole **4a24a** penetrating through the bottom wall **4a242** is disposed on the bottom wall **4a242** of the frame

424, and an annular flange **4a243** surrounding the installation through hole **4a24a** is disposed on a surface that is of the bottom wall **4a242** and that faces away from the circumferential wall **4a241**. The first magnetic circuit system **4a23** is fastened to the installation through hole **4a24a**, and is limited by being surrounded by the annular flange **4a243**. Certainly, it may be understood that, when the installation through hole **4a24a** and the annular flange **4a243** are not disposed on the first frame **4a24**, the first magnetic circuit system **4a23** may be disposed in the first frame **4a24**.

It may be understood that the first voice coil **4a22** is connected to the side that is of the first dome **4a213** and that faces away from the sound output hole **110**, and the end that is of the first voice coil **4a22** and that is away from the first diaphragm assembly **4a21** cooperates with the magnetic gap **4a23a** of the first magnetic circuit system **4a23**. In this way, compared with a solution in which the first voice coil **4a22** is connected to a side that is of the first dome **4a213** and that faces the sound output hole **110**, and the end that is of the first voice coil **4a22** and that is away from the first diaphragm assembly **4a21** cooperates with the magnetic gap **4a23a** of the first magnetic circuit system **4a23**, an outer surface that is of the first diaphragm assembly **4a21** and that faces the sound output hole **110** can be not blocked by the first magnetic circuit system **4a23** or the first voice coil **4a22**, to help ensure a sound output area of the first diaphragm assembly **4a21**, and further improve a sound output effect of the first speaker unit **4a**.

Still referring to FIG. 18, the magnetic gap **4a23a** includes a first gap part **4a23a1** and a second gap part **4a23a2**. The first gap part **4a23a1** and the second gap part **4a23a2** are arranged and connected in the circumferential direction of the first frame **4a24**. The first gap part **4a23a1** linearly extends in the circumferential direction of the first frame **4a24**. In this way, an extending path of the first gap part **4a23a1** in the circumferential direction of the first frame **4a24** can be the same as the extending path of the first voice coil part **4a221** in the circumferential direction of the first frame **4a24**, so that the first gap part **4a23a1** is adapted to the first voice coil part **4a221** and allows the first voice coil part **4a221** to extend into the first gap part **4a23a1**. The second gap part **4a23a2** extends to be arc-shaped in the circumferential direction of the first frame **4a24**. In this way, an extending path of the second gap part **4a23a2** in the circumferential direction of the first frame **4a24** can be the same as the extending path of the second voice coil part **4a222** in the circumferential direction of the first frame **4a24**, so that the second gap part **4a23a2** is adapted to the second voice coil part **4a222** and allows the second voice coil part **4a222** to extend into the second gap part **4a23a2**.

According to the first magnetic circuit system **4a23** in this embodiment of this application, the magnetic gap **4a23a** includes the first gap part **4a23a1** and the second gap part **4a23a2**, the first gap part **4a23a1** is adapted to the first voice coil part **4a221**, and the second gap part **4a23a2** is adapted to the second voice coil part **4a222**. In this way, a shape of the entire magnetic gap **4a23a** can be adapted to a shape of the first voice coil **4a22**. This helps ensure cooperation reliability between the first voice coil **4a22** and the first magnetic circuit system **4a23**. Therefore, when the first voice coil **4a22** cooperates with the first magnetic circuit system **4a23** to drive the first diaphragm assembly **4a21** to vibrate, this can help ensure uniformity of a driving force for the first diaphragm assembly **4a21** in the circumferential direction of the first frame **4a24**, and avoid, to at least a specific degree, a problem that rolling vibration occurs on the first diaphragm assembly **4a21**.

Specifically, a width of the first gap part **4a23a1** is less than a width of the second gap part **4a23a2**. A smaller width of the magnetic gap indicates a larger driving force generated for the diaphragm assembly after the magnetic circuit system cooperates with the voice coil, and a larger width of the magnetic gap indicates a smaller driving force generated for the diaphragm assembly after the magnetic circuit system cooperates with the voice coil. Therefore, for the first speaker unit **4a** that is not symmetrically disposed by using the plane **m2m2** as a symmetry plane, when the first diaphragm assembly **4a21** vibrates, a driving force received on a side that is of the first diaphragm assembly **4a21** and that is close to the first part **4a2411** is less than a driving force received on a side that is of the first diaphragm assembly **4a21** and that is close to the second part **4a2412**, and consequently there is a risk of rolling vibration. The width of the first gap part **4a23a1** is less than the width of the second gap part **4a23a2**. This helps increase the driving force received on the side that is of the first diaphragm assembly **4a21** and that is close to the first part **4a2411**, thereby improving, to at least a specific degree, uniformity of a driving force received by the first diaphragm assembly **4a21** in the circumferential direction of the first frame **4a24**, and avoiding a problem that rolling vibration occurs on the first diaphragm assembly **4a21**.

Still referring to FIG. 18, the first magnetic circuit system **4a23** includes an edge magnetic part **4a231** and a first central magnetic part **4a232**. The edge magnetic part **4a231** is located on the outer circumference of the first central magnetic part **4a232**, to define the magnetic gap **4a23a** with the first central magnetic part **4a232**. A magnetization direction of the edge magnetic part **4a231** is opposite to a magnetization direction of the first central magnetic part **4a232**, so that the edge magnetic part **4a231** and the first central magnetic part **4a232** can form a magnetic loop for driving the first voice coil **4a22** to move. For example, along an axial direction of the first frame **4a24** and in a direction away from the first diaphragm assembly **4a21**, the magnetization direction of the edge magnetic part **4a231** is from a north (N) pole to a south (S) pole, and the magnetization direction of the first central magnetic part **4a232** is from a south (S) pole to a north (N) pole.

Still referring to FIG. 18, the edge magnetic part **4a231** may be formed to be annular, and the edge magnetic part **4a231** includes a first subpart **4a231a** and a second subpart **4a231b**. The first subpart **4a231a** and the second subpart **4a231b** are arranged and connected in the circumferential direction of the first frame **4a24**.

Still referring to FIG. 18, and referring to FIG. 17B, the first subpart **4a231a** is in a shape of a slate, and the first subpart **4a231a** is located between the first part **4a2411** and the second subpart **4a231b**. In this way, an extending path of the first subpart **4a231a** in the circumferential direction of the first frame **4a24** may be the same as the extending path of the first part **4a2411** in the circumferential direction of the first frame **4a24**. The second subpart **4a231b** extends to be arc-shaped along the circumferential direction of the first frame **4a24**, and the second subpart **4a231b** is located between the second part **4a2412** and the first subpart **4a231a**. In this way, an extending path of the second subpart **4a231b** in the circumferential direction of the first frame **4a24** may be the same as the extending path of the second part **4a2412** in the circumferential direction of the first frame **4a24**. Specifically, the second subpart **4a231b** and the second part **4a2412** have a same central axis.

Refer to FIG. 19. FIG. 19 is a schematic diagram of a structure of cooperation between the edge magnetic part

4a231 and a second central magnetic part **4a233** of the first magnetic circuit system **4a23** shown in FIG. 18. To effectively support the first central magnetic part **4a232**, the first magnetic circuit system **4a23** further includes the second central magnetic part **4a233**, the second central magnetic part **4a233** blocks an end that is of the edge magnetic part **4a231** and that is away from the first diaphragm assembly **4a21**, and the first central magnetic part **4a232** and the second central magnetic part **4a233** are disposed in a stacked manner.

The second central magnetic part **4a233** and the edge magnetic part **4a231** may be an integrally formed member. That is, the second central magnetic part **4a233** and the edge magnetic part **4a231** may be an integral structure. The second central magnetic part **4a233** and the edge magnetic part **4a231** may alternatively be connected through gluing, clamping, threading, or the like.

Specifically, the second central magnetic part **4a233** may be a magnetic conductive material member. In this way, leakage of a magnetic force line may be restricted by using the second central magnetic part **4a233**, to increase magnetic induction intensity of the first magnetic circuit system **4a23**. Certainly, this application is not limited thereto. In some other examples, the second central magnetic part **4a233** may be a magnetic body. Specifically, the magnetic body is a magnet or magnetic steel.

Refer to FIG. 20, and refer to FIG. 18. FIG. 20 is a schematic diagram of cooperation between the first central magnetic part **4a232** and a magnetic conductive yoke **4a234** of the first magnetic circuit system **4a23** shown in FIG. 18. An outer circumferential surface of the first central magnetic part **4a232** includes a first surface **4a232a** and a second surface **4a232b**.

The first surface **4a232a** and the second surface **4a232a** are arranged and connected in the circumferential direction of the first frame **4a24**. The first surface **4a232a** is a plane parallel to the first contour surface **4aa**, and the first surface **4a232a** corresponds to and is spaced apart from the first subpart **4a231a**, to define the first gap part **4a23a1**.

The second surface **4a232b** is an arc-shaped surface extending along the circumferential direction of the first frame **4a24**, and the second surface **4a232b** corresponds to and is spaced apart from the second subpart **4a231b**, to define the second gap part **4a23a2**. Specifically, the second surface **4a232b** and the second contour surface **4ab** have a same central axis.

In this way, the first magnetic circuit system **4a23** in this embodiment of this application can define the magnetic gap **4a23a** whose shape is adapted to the shape of the first voice coil **4a22**. This helps ensure cooperation reliability between the first voice coil **4a22** and the first magnetic circuit system **4a23**. Therefore, when the first voice coil **4a22** cooperates with the first magnetic circuit system **4a23** to drive the first diaphragm assembly **4a21** to vibrate, this ensures uniformity of a driving force for the first diaphragm assembly **4a21** in the circumferential direction of the first frame **4a24**, and avoids a problem that rolling vibration occurs on the first diaphragm assembly **4a21**.

In some examples, both the edge magnetic part **4a231** and the first central magnetic part **4a232** may be magnetic bodies. For example, both the edge magnetic part **4a231** and the first central magnetic part **4a232** are magnets or magnetic steel. Certainly, this application is not limited thereto.

In another embodiment, one of the edge magnetic part **4a231** and the first central magnetic part **4a232** is a magnetic body, and the other is a magnetic conductive material member.

To increase magnetic induction intensity of the first magnetic circuit system **4a23**, referring to FIG. 20, and referring to FIG. 18, the first magnetic circuit system **4a23** further includes the magnetic conductive yoke **4a234**. The magnetic conductive yoke **4a234** is disposed on a side that is of the first central magnetic part **4a232** and that faces the first diaphragm assembly **4a21**, to restrict leakage of the magnetic force line, thereby improving a driving force for the first diaphragm assembly **4a21**.

Specifically, an outer circumferential surface of the magnetic conductive yoke **4a234** is flush with the outer circumferential surface of the first central magnetic part **4a232** in an axial direction of the first magnetic circuit system **4a23**. Therefore, a shape of the outer circumferential surface of the magnetic conductive yoke **4a234** is the same as a shape of the outer circumferential surface of the first central magnetic part **4a232**, and the magnetic conductive yoke **4a234** is adapted to the first central magnetic part **4a232**. This helps further improve a restriction effect of the magnetic conductive yoke **4a234** for the magnetic force line, and increase magnetic induction intensity of the first magnetic circuit system **4a23**. Furthermore, the magnetic conductive yoke **4a234** does not affect the magnetic gap **4a23a**, thereby helping improve adaption between the first magnetic circuit system **4a23** and the first voice coil **4a22**.

Based on the foregoing embodiments, refer to FIG. 21 and FIG. 22. FIG. 21 is a schematic diagram of a structure of the second speaker unit **4b** in the headset **100** shown in FIG. 6. FIG. 22 is a schematic diagram of a structure of a cross section of the second speaker unit **4b** shown in FIG. 21 along a line E-E. In this embodiment, the second speaker unit **4b** may be a moving-iron tweeter. The second speaker unit **4b** may include a protective casing **4b1**, a second diaphragm assembly **4b21**, a spring plate **4b22**, a transmission rod **4b23**, a second magnetic circuit system **4b24**, and a second voice coil **4b25**.

It may be understood that FIG. 21, FIG. 22, and the following related accompanying drawings merely show examples of some components included in the second speaker unit **4b**. Actual shapes, actual sizes, actual positions, and actual structures of these components are not limited by FIG. 21, FIG. 22, and the following accompanying drawings.

The protective casing **4b1** is configured to protect the second diaphragm assembly **4b21**, the spring plate **4b22**, the transmission rod **4b23**, the second magnetic circuit system **4b24**, the second voice coil **4b25**, and the like as a carrier of the components in the second speaker unit **4b**.

A sound output channel **4b11** is formed on a side that is of the protective casing **4b1** and that is adjacent to the sound output hole **110**, and sound of the second speaker unit **4b** can be emitted through the sound output channel **4b11**, so that both the second speaker unit **4b** and the first speaker unit **4a** can emit sound toward the sound output hole **110**.

A material of the protective casing **4b1** includes but is not limited to metal, plastic, and a combination of metal and plastic. In some embodiments, the material of the protective casing **4b1** is plastic. Plastic has low costs and is easy to form. This helps reduce processing costs of the second speaker unit **4b**. In some other examples, to improve structural strength of the protective casing **4b1**, the material of the protective casing **4b1** may be metal.

The protective casing **4b1** extends along the sound output direction of the sound output hole **110**, that is, a length direction of the protective casing **4b1** is the same as the

sound output direction of the sound output hole **110**. Specifically, referring to FIG. 21, a shape of the protective casing **4b1** may be a cuboid.

Certainly, this application is not limited thereto. In some other examples, refer to FIG. 23. FIG. 23 is a schematic diagram of a partial structure of the headset **100** according to still some other embodiments of this application. A cross section of the protective casing **4b1** may alternatively be formed as a small semicircle, and a surface that is of the protective casing **4b1** and that faces away from the first speaker unit **4a** may be adapted to the first inner circumferential surface region **10a**. This disposition helps make full use of the space of the housing **1** to implement compactness of a structure, and facilitates cooperation between the second speaker unit **4b** and the first speaker unit **4a** to separate the front cavity **X1** and the rear cavity **X2** of the first speaker unit **4a**.

The protective casing **4b1** may be an integral structure, or may be formed by assembling a plurality of parts. In some embodiments, still referring to FIG. 22, the protective casing **4b1** includes a first casing part **4b1a** and a second casing part **4b1b**. The protective casing **4b1** is formed by assembling the first casing part **4b1a** and the second casing part **4b1b**. This can facilitate separate processing of the first casing part **4b1a** and the second casing part **4b1b**, to help simplify mold structures of the first casing part **4b1a** and the second casing part **4b1b**, thereby reducing forming difficulty of the first casing part **4b1a** and the second casing part **4b1b**, and reducing processing and manufacturing difficulty of the protective casing **4b1**.

Still referring to FIG. 22, the second diaphragm assembly **4b21** is disposed in the protective casing **4b1**. The second diaphragm assembly **4b21** is parallel to an axial direction of the first speaker unit **4a**. Compared with a solution in which the second diaphragm assembly **4b21** is perpendicular to the axial direction of the first speaker unit **4a**, this helps ensure an effective vibration area of the second diaphragm assembly **4b21**, and also helps reduce a thickness size of the second speaker unit **4b** in a radial direction of the first speaker unit **4a**.

The second speaker unit **4b** divides space in the protective casing **4b1** into a front cavity **k1** and a rear cavity **k2** by using the second diaphragm assembly **4b21**. In this way, the front cavity **k1** and the rear cavity **k2** are arranged in the radial direction of the first speaker unit **4a**. In some examples, the front cavity **k1** is located on a side that is of the rear cavity **k2** and that is away from the first speaker unit **4a**. This disposition helps reduce sound output interference between the first speaker unit **4a** and the second speaker unit **4b**. In some other examples, the rear cavity **k2** is located on a side that is of the front cavity **k1** and that is away from the first speaker unit **4a**.

Refer to FIG. 24. FIG. 24 is a schematic diagram of a structure of the second diaphragm assembly **4b21** of the second speaker unit **4b** shown in FIG. 21. The second diaphragm assembly **4b21** includes a second connection part **4b21a**, a second folded ring **4b21b**, and a second dome **4b21c**.

The second connection part **4b21a** is in a shape of an annular plate, and the second connection part **4b21a** is a rectangular ring with round corners.

Referring to FIG. 24, and referring to FIG. 22, a step part **4b12** is disposed on an inner circumferential surface of the protective casing **4b1**, and the second connection part **4b21a** is disposed on the step part **4b12** in a stacked manner. A connection relationship between the second connection part **4b21a** and the step part **4b12** includes but is not limited to

gluing. Certainly, in some other examples, the step part may not be disposed in the protective casing **4b1**. Instead, the second connection part **4b21a** is disposed in a shape of an annular cylinder, and the second connection part **4b21a** is connected to the inner circumferential surface of the protective casing **4b1**.

The second folded ring **4b21b** is disposed on the outer circumference of the second dome **4b21c** and surrounded by the second connection part **4b21a**. The second folded ring **4b21b** is in a shape of a rectangular ring with round corners. The second folded ring **4b21b** is recessed toward a side close to the rear cavity **K2**, to form an arc-shaped or approximately arc-shaped cross section. This disposition can save space of the front cavity **K1**. Certainly, this application is not limited thereto. In another embodiment, the second folded ring **4b21b** is recessed toward a side close to the front cavity **K1**, to form an arc-shaped or approximately arc-shaped cross section.

In some examples, the second diaphragm assembly **4b21** may be an integrally formed member. That is, the second connection part **4b21a**, the second folded ring **4b21b**, and the second dome **4b21c** are integrally formed and connected as a whole. This disposition facilitates simplification of a processing technique and reduction of production costs, and can also improve connection strength between the second connection part **4b21a** and the second folded ring **4b21b** and connection strength between the second folded ring **4b21b** and the second dome **4b21c**. Certainly, this application is not limited thereto. In another embodiment, the second connection part **4b21a**, the second folded ring **4b21b**, and the second dome **4b21c** may be separately processed and manufactured, and then connected through gluing or the like.

Still referring to FIG. 22, the spring plate **4b22** is disposed in the rear cavity **K2** of the second speaker unit **4b**, and is configured to provide a driving force for vibration of the second diaphragm assembly **4b21**. A material of the spring plate **4b22** includes but is not limited to metal.

Refer to FIG. 25. FIG. 25 is a schematic diagram of a structure of the spring plate **4b22** of the second speaker unit **4b** shown in FIG. 21. The spring plate **4b22** includes a first plate body **4b221**, a second plate body **4b222**, and a connection plate body **4b223**.

The first plate body **4b221** is in a shape of a rectangular plate. The first plate body **4b221** is disposed in parallel to the second diaphragm assembly **4b21**. The second plate body **4b222** is in a shape of a rectangular plate. The second plate body **4b222** is disposed in parallel to the second diaphragm assembly **4b21**, and the second plate body **4b222** is located on a side that is of the first plate body **4b221** and that is away from the second diaphragm assembly **4b21**. A size of the second plate body **4b222** may be the same as a size of the first plate body **4b221**.

A support body **4b224** beyond an edge of the first plate body **4b221** is disposed at one end of the second plate body **4b222**, and the support body **4b224** is in a shape of a triangle. In some examples, the support body **4b224** and the second plate body **4b222** may be an integrally formed member, that is, the support body **4b224** and the second plate body **4b222** are connected as an integral structure. In some other examples, the support body **4b224** and the second plate body **4b222** may be connected through gluing, clamping, welding, threading, or the like.

A shape of the connection plate body **4b223** includes but is not limited to a "C" shape and a "V" shape. The connection plate body **4b223** is connected between an end that is of the second plate body **4b222** and that is away from the

support body **4b224** and an end that is of the first plate body **4b221** and that is away from the support body **4b224**.

The spring plate **4b22** may be an integrally formed member. That is, the first plate body **4b221**, the second plate body **4b222**, and the connection plate body **4b223** are connected as a whole. This disposition facilitates simplification of a processing technique and reduction of production costs, and can also improve connection strength between the first plate body **4b221** and the connection plate body **4b223** 10 and connection strength between the second plate body **4b222** and the connection plate body **4b223**. Certainly, this application is not limited thereto. In another embodiment, the first plate body **4b221**, the second plate body **4b222**, and the connection plate body **4b223** 15 may be separately processed and manufactured, and then connected through gluing, welding, or the like.

Still referring to FIG. 22, the transmission rod **4b23** is in a shape of a rod, the transmission rod **4b23** is connected 20 between the support body **4b224** and the second dome **4b21c**, and the transmission rod **4b23** is perpendicularly disposed with the second plate body **4b222**. Vibration of the spring plate **4b22** may be transmitted to the second diaphragm assembly **4b21** through connection of the transmission rod **4b23**, to cause the second speaker unit **4b** to emit sound.

A material of the transmission rod **4b23** includes but is not limited to metal or hard plastic. A connection manner between the transmission rod **4b23** and the second plate body **4b222** includes but is not limited to gluing, welding, clamping, or threading. A connection manner between the transmission rod **4b23** and the second diaphragm assembly **4b21** includes but is not limited to gluing, welding, clamping, or threading.

Refer to FIG. 26, and refer to FIG. 22. FIG. 26 is a schematic diagram of a structure of the second magnetic circuit system **4b24** of the second speaker unit **4b** shown in FIG. 21. The second magnetic circuit system **4b24** is located in the rear cavity **K2** of the second speaker unit **4b**. The second magnetic circuit system **4b24** includes a magnetic conductive part **4b241** and two magnetic body parts **4b242**.

The magnetic conductive part **4b241** is in a shape of a rectangular ring. An axial direction of the magnetic conductive part **4b241** is the same as the axial direction of the first frame **4a24**. The first plate body **4b221** is supported on a surface of a side that is of the magnetic conductive part **4b241** and that is adjacent to the second diaphragm assembly **4b21**. A connection manner between the first plate body **4b221** and the magnetic conductive part **4b241** includes but is not limited to gluing or clamping.

The two magnetic body parts **4b242** are disposed in the magnetic conductive part **4b241** and are oppositely disposed in a radial direction of the magnetic conductive part **4b241**.

A shape of the magnetic body part **4b242** includes but is not limited to a cuboid shape, a cylinder shape, or a special shape. Magnetization directions of the two magnetic body parts **4b242** are opposite. For example, an end that is of one magnetic body part **4b242** and that is close to a central axis of the magnetic conductive part **4b241** is an N pole, and an end that is of the magnetic body part **4b242** and that is away from the central axis of the magnetic conductive part **4b241** is an S pole; and an end that is of the other magnetic body part **4b242** and that is close to the central axis of the magnetic conductive part **4b241** is an S pole, and an end that is of the magnetic body part **4b242** and that is away from the central axis of the magnetic conductive part **4b241** is an N pole.

31

Still referring to FIG. 22, the second plate body 4b222 penetrates from one end of the axial direction of the magnetic conductive part 4b241 to the other end of the axial direction of the magnetic conductive part 4b241, so that the support body 4b224 is located outside the magnetic conductive part 4b241, and the second plate body 4b222 is located between the two magnetic body parts 4b242.

The second voice coil 4b25 is located on a side that is of the axial direction of the magnetic conductive part 4b241 and that is adjacent to the connection plate body 4b223, and the second voice coil 4b25 surrounds the outer circumference of the second plate body 4b222.

When the second voice coil 4b25 is energized, the second voice coil 4b25 may generate a magnetic field, so that the second plate body 4b222 located in the second voice coil 4b25 is magnetized to generate magnetic poles. In this way, a driving force for driving the second plate body 4b222 to vibrate along a spacing direction of the two magnetic body parts 4b242 may be formed between the second voice coil 4b25 and the magnetic body parts 4b242, vibration of the second plate body 4b222 can drive the transmission rod 4b23 to vibrate, vibration of the transmission rod 4b23 further drives the second diaphragm assembly 4b21 to vibrate, and vibration of the second diaphragm assembly 4b21 can push air in the front cavity K1 to vibrate to generate a sound wave. The sound wave is emitted through the sound output channel 4b11.

In the descriptions of this specification, specific features, structures, materials, or characteristics may be combined in any one or more embodiments or examples in a suitable manner.

Finally, it should be noted that the foregoing embodiments are only used to describe the technical solutions of this application, but are not used to limit this application. Although this application is described in detail with reference to the foregoing embodiments, it should be understood by a person of ordinary skill in the art that the technical solutions described in the foregoing embodiments may still be modified, or some technical features thereof are equivalently replaced. These modifications or replacements do not make the essence of the corresponding technical solutions depart from the spirit and scope of the technical solutions of the embodiments of this application.

What is claimed is:

1. A speaker assembly, used for a headset, wherein the headset comprises a housing, and the speaker assembly comprises:

a first speaker, wherein the first speaker comprises a first diaphragm assembly and an outer circumferential surface, and wherein an outer surface of the first diaphragm assembly faces a first side and a first contour surface of the first speaker is arranged along a circumferential direction of the first speaker, the first contour surface being configured to form a gap between the first contour surface and an inner circumferential surface of the housing; and

a second speaker, wherein the second speaker is located within the gap between the first speaker and the inner circumferential surface of the housing on one side of the circumferential direction of the first speaker, the second speaker emits sound toward the first side, and sound emission frequency of the second speaker is greater than sound emission frequency of the first speaker.

2. The speaker assembly according to claim 1, wherein the outer circumferential surface of the first speaker comprises the first contour surface and a second contour surface, and

32

the first contour surface and the second contour surface are arranged and connected along the circumferential direction of the first speaker;

the inner circumferential surface of the housing comprises a first inner circumferential surface region and a second inner circumferential surface region, and the first inner circumferential surface region and the second inner circumferential surface region are arranged and connected along a circumferential direction of the housing; and

the first contour surface is opposite to and spaced apart from the first inner circumferential surface region, the second contour surface is adapted to the second inner circumferential surface region, and the second speaker is located between the first contour surface and the first inner circumferential surface region.

3. The speaker assembly according to claim 2, wherein both the second inner circumferential surface region and the second contour surface are arc-shaped surfaces that extend along the circumferential direction of the housing and that are arched away from the first contour surface.

4. The speaker assembly according to claim 3, wherein the first contour surface is a plane, or the first contour surface is an arc-shaped surface arched toward the first inner circumferential surface region.

5. The speaker assembly according to claim 2, wherein the first speaker comprises a first frame, the first diaphragm assembly is supported on the first frame and disposed based on a same central axis as the first frame, a circumferential wall of the first frame comprises a first part and a second part, the first part and the second part are arranged and connected along a circumferential direction of the first frame, a surface that is of the first part and that faces away from the second part is formed as the first contour surface, and a surface that is of the second part and that faces away from the first part is formed as the second contour surface.

6. The speaker assembly according to claim 5, wherein the first diaphragm assembly has a first folded ring, the first folded ring comprises a first segment and a second segment, the first segment and the second segment are arranged and connected in the circumferential direction of the first frame, an extending path of the first segment along the circumferential direction of the first frame is the same as an extending path of the first part along the circumferential direction of the first frame, an extending path of the second segment along the circumferential direction of the first frame is the same as an extending path of the second part along the circumferential direction of the first frame, the first segment is located between the first part and the second segment, and the second segment is located between the first segment and the second part.

7. The speaker assembly according to claim 6, wherein the first segment is equal to the second segment in width.

8. The speaker assembly according to claim 5, wherein an annular groove recessed in a direction away from the central axis of the first frame is disposed on an inner circumferential surface of the first frame, the annular groove extends along the circumferential direction of the first frame and the annular groove penetrates to an end surface of an open end of the first frame, and an outer edge of the first diaphragm assembly is accommodated in the annular groove and fastened to a bottom surface of the annular groove.

9. The speaker assembly according to claim 5, wherein the first speaker comprises a first voice coil, and the first voice coil is connected to an inner surface of the first diaphragm assembly; and

the first voice coil comprises a first voice coil part and a second voice coil part that are arranged and connected in the circumferential direction of the first frame, an extending path of the first voice coil part along the circumferential direction of the first frame is the same as the extending path of the first part along the circumferential direction of the first frame, the first voice coil part is located between the first part and the second voice coil part, an extending path of the second voice coil part along the circumferential direction of the first frame is the same as the extending path of the second part along the circumferential direction of the first frame, and the second voice coil part is located between the second part and the first voice coil part.

10. The speaker assembly according to claim 9, wherein the first speaker comprises a first magnetic circuit system, the first magnetic circuit system is fastened to the first frame, and the first magnetic circuit system has an annular magnetic gap; and

15 the magnetic gap comprises a first gap part and a second gap part, the first gap part and the second gap part are arranged and connected in the circumferential direction of the first frame, the first gap part is adapted to the first voice coil part, and the second gap part is adapted to the second voice coil part.

20 11. The speaker assembly according to claim 10, wherein a width of the first gap part is less than a width of the second gap part.

25 12. The speaker assembly according to claim 2, wherein a surface that is of the second speaker and that faces away from the first speaker is adapted to the first inner circumferential surface region.

30 13. The speaker assembly according to claim 1, wherein an outer circumferential contour of the first speaker is elliptical, and the second speaker is located at one end of a length direction of a short axis of the first speaker.

35 14. The speaker assembly according to claim 1, wherein the first speaker is a moving-coil woofer.

40 15. The speaker assembly according to claim 1, wherein the second speaker is a moving-iron tweeter or a planar voice coil tweeter.

16. A headset, comprising:

45 a housing, wherein a sound output hole is formed on the housing; and

48 a speaker assembly, wherein the speaker assembly comprises:

50 a first speaker, wherein the first speaker comprises a first diaphragm assembly and an outer circumferential surface, and an outer surface of the first diaphragm assembly faces a first side and a first contour surface of the first speaker is arranged along a circumferential direction of the first speaker, the first contour surface being configured to form a gap between the first contour surface and an inner circumferential surface of the housing, and

a second speaker, wherein the second speaker is located within the gap between the first speaker and the inner circumferential surface of the housing on one side of a circumferential direction of the first speaker, the second speaker emits sound toward the first side, and sound emission frequency of the second speaker is greater than sound emission frequency of the first speaker,

wherein the first speaker is disposed in the housing, the outer surface of the first diaphragm assembly faces the sound output hole, the second speaker is disposed in the housing, and the second speaker emits sound toward the sound output hole.

17. The headset according to claim 16, wherein the outer circumferential surface of the first speaker comprises the first contour surface and a second contour surface, and the first contour surface and the second contour surface are arranged and connected along the circumferential direction of the first speaker;

20 the inner circumferential surface of the housing comprises a first inner circumferential surface region and a second inner circumferential surface region, and the first inner circumferential surface region and the second inner circumferential surface region are arranged and connected along a circumferential direction of the housing; and

25 the first contour surface is opposite to and spaced apart from the first inner circumferential surface region, the second contour surface is adapted to the second inner circumferential surface region, and the second speaker is located between the first contour surface and the first inner circumferential surface region.

30 18. The headset according to claim 17, wherein both the second inner circumferential surface region and the second contour surface are arc-shaped surfaces that extend along the circumferential direction of the housing and that are arched away from the first contour surface.

35 19. The headset according to claim 18, wherein the first contour surface is a plane, or the first contour surface is an arc-shaped surface arched toward the first inner circumferential surface region.

40 20. The headset according to claim 17, wherein the first speaker comprises a first frame, the first diaphragm assembly is supported on the first frame and disposed based on a same central axis as the first frame, a circumferential wall of the first frame comprises a first part and a second part, the first part and the second part are arranged and connected along a circumferential direction of the first frame, a surface that is of the first part and that faces away from the second part is formed as the first contour surface, and a surface that is of the second part and that faces away from the first part is formed as the second contour surface.
